US00D990225S

(12) **United States Design Patent** (10) **Patent No.:** **US D990,225 S**
Shewan et al. (45) **Date of Patent:** **** Jun. 27, 2023**

(54) **BAKEWARE LID**

(71) Applicant: **Helen of Troy Limited**, St. Michael (BB)
(72) Inventors: **Erik Shewan**, Tarrytown, NY (US); **Juliette Laroche**, New York, NY (US)
(73) Assignee: **Helen of Troy Limited**, St. Michael (BB)

(**) Term: **15 Years**

(21) Appl. No.: **29/817,238**

(22) Filed: **Nov. 30, 2021**

(51) **LOC (14) Cl.** **07-02**
(52) **U.S. Cl.**
USPC **D7/391; D9/435**

(58) **Field of Classification Search**

(57) **CLAIM**

The ornamental design for a bakeware lid, as shown and described.

DESCRIPTION

FIG. 1 is a perspective view of a bakeware lid showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1; and,

FIG. 8 is a bottom perspective view of FIG. 1.

The broken lines in the drawings depict portions of the bakeware lid that form no part of the claimed design.

1 Claim, 5 Drawing Sheets
